(57) **CLAIM**

The ornamental design for a game, as shown and described.

DESCRIPTION

FIG. 1 is an exploded perspective view of a game, showing my new design;

FIG. 2 is a top plan view of the invention;

FIG. 3 is a front elevational view of a repositionable “sand trap” obstacle of the invention, the rear elevational view being a mirror image thereof; and,

FIG. 4 is a left-side elevational view of the repositionable “sand trap” obstacle of the invention, the right-side elevational view being a mirror image thereof.

The broken lines showing a pool table base in FIG. 1 and a plurality of balls in FIGS. 1 and 2 are included for the purpose of illustrating the invention in use, and form no part of the claimed design.
